[57] CLAIM

The ornamental design for a frame for physical exerciser, as shown and described.

DESCRIPTION

FIG. 1 is a perspective view of a frame for physical exerciser showing my new design;

FIG. 2 is a left side elevational view thereof and a mirror image of a right side view;

FIG. 3 is a front elevational view thereof;

FIG. 4 is a rear elevational view thereof;

FIG. 5 is a top view thereof; and,

FIG. 6 is a bottom plan view thereof.
